Primary Examiner — Ian Simmons*Assistant Examiner* — Eleni H Aldridge(74) *Attorney, Agent, or Firm* — Altis Law Group, Inc.(57) **CLAIM**

The ornamental design for a diaphragm, as shown.

DESCRIPTION

FIG. 1 is a perspective view of a diaphragm showing my new design.

FIG. 2 is a front elevational view thereof.

FIG. 3 is a rear elevational view thereof.

FIG. 4 is a left side elevational view thereof.

FIG. 5 is a right side elevational view thereof.

FIG. 6 is a top plan view thereof.

FIG. 7 is a bottom plan view thereof.

FIG. 8 is a cross-sectional view of the diaphragm, corresponding to A-A of FIG. 2, and illustrating the contour and outline of the diaphragm; and,

FIG. 9 is a cross-sectional view of the diaphragm, corresponding to B-B of FIG. 2, and illustrating the contour and outline of the diaphragm.
